UNITED STATES PATENT OFFICE.

GEORGE W. RAYNOR, OF WILLIAMSON SCHOOL, PENNSYLVANIA.

COMBINED CARPENTER'S BENCH AND VISE.

SPECIFICATION forming part of Letters Patent No. 710,713, dated October 7, 1902.

Application filed April 14, 1902. Serial No. 102,735. (No model.)

To all whom it may concern:

Be it known that I, GEORGE W. RAYNOR, a citizen of the United States of America, residing at Williamson School, in the county of 5 Delaware and State of Pennsylvania, have invented a certain new and useful Improvement in a Combined Carpenter's Bench and Vise, of which the following is a true and exact description, reference being had to the accompanying drawings, which form a part thereof.

My invention has relation to carpenters' benches, and has for its object to provide such a bench with a vise, such as is ordinarily used by carpenters, which can be shifted from 15 an operative position to a position beneath the bench entirely out of the way of the user; and my invention consists, broadly speaking, in the combination, with a carpenter's bench, of a vise and means for supporting such a 20 vise upon the bench either in operative position or in a position beneath the bench.

The nature of my invention and what I believe to be the best way of carrying it into practical effect will be best understood as described in connection with the drawings, in 25 which it is illustrated, and in which—

Figure 1 is a side elevation of the end of the bench upon which the vise is secured, the vise being shown in operative position. Fig. 30 2 is a similar view with the vise in non-operative and retracted position. Fig. 3 is a horizontal section on the line 3 3 of Fig. 1, and Fig. 4 a horizontal section on the line 4 4 of Fig. 1.

35 A A, &c., indicate the legs of the bench; B and B', the upper and lower cross-timbers; B² B², outwardly-extending timbers secured to the legs and supporting apron-pieces C C, the inner portions C' of which are hinged to the 40 stationary portions at C³ and shaped so that they can be folded back at right angles, the ends of the timbers B² being cut away, as shown at b², for this purpose.

D is the top or table of the bench.

45 E and E' are brackets firmly secured to the legs of the bench. They are formed with retaining and supporting notches, as indicated at E² and E³, the notches E² being both farther forward and at a higher level than the 50 notches E³ and the two notches in each bracket being connected by a guiding slot or groove, (indicated at E⁴ E⁵ E⁶.)

The vise is of usual construction, consisting of two stout timbers F and H, the upper ends F' and H' constituting the jaws of the 55 vise and the two timbers being pivotally connected together at or near the bottom. The pivotal connection shown is provided for by securing to the inner vise-timber F pins, (indicated at F².) which pins are adapted to engage in the notches I' of a bar I, pivoted at H³ to a casting H², secured on the upper vise-timber H. This enables the two timbers to be moved at the bottom to accommodate the size of the work which the jaws have to engage. 65

J is the vise-screw, turned by a lever J' and secured to the outer vise-timber H through a casting H⁴, the screw passing through a nut G, secured in the inner timber F. In all of 70 these features the vise is of usual and ordinary construction.

To the inner timber F of the vise I secure brackets, (shown at F³ F⁴.) these brackets supporting at their ends rods or pins F⁵ F⁶, 75 which project into the slots of the brackets E E' and are adapted to lie and be engaged by the notches E² and E³, as shown. In operative position the brackets connected with the vise are supported in the upper notches 80 E² of the bench-brackets, as shown in Fig. 1, and when the vise is no longer required for use the operative simply lifts it slightly and draws it forward through the groove E⁴, then permits it to move downward through the 85 grooves E⁵, and thrusts it backward through the grooves E⁶ until the pins F⁵ F⁶ engage in the notches E³, as shown in Fig. 2. In this way the vise is entirely retracted beneath the table of the bench out of sight and out of the 90 way, but in position to be at once restored to operative position by simply reversing the above-described movements.

Having now described my invention, what I claim as new, and desire to secure by Letters 95 Patent, is—

1. In combination with a carpenter's work-bench, a vise and means for supporting said vise on the bench either in operative position or in depressed and retracted position under 100 the table of the bench.

2. In combination with a carpenter's work-bench, a vise, means for supporting said vise on the bench either in operative position or

in depressed and retracted position under the table of the bench, and guides regulating the movements of the vise from and to operative position.

5 3. In combination with a carpenter's work-bench, brackets E E' secured beneath the bench and formed with supporting-recesses E² E³ connected by slots, a vise and brackets F³ F⁴ secured to the vise and resting in brackets E E' as described whereby the vise can be shifted from operative position to a position beneath the table.

4. In combination with a carpenter's work-bench, a vise consisting of two bars F and H, 15 adjustable means for pivotally securing the lower ends of said bars together at determined distances apart, and means acting on the upper parts of the beams for drawing the upper or jaw ends of the beams together.

20 5. In combination with a carpenter's work-bench, a vise consisting of two bars F and H,

a notched bar I pivoted to the lower end of beam H, a pin or detent in bar F adapted to be engaged by the notches in bar I and a screw J connected with the upper portions of 25 the jaw-beams whereby they are drawn together.

6. In combination with a carpenter's work-bench, a vise consisting of two bars F and H, 30 a notched bar I pivoted to the lower end of beam H, a pin or detent in bar F adapted to be engaged by the notches in bar I and a screw J connected with the upper portions of the jaw-beams whereby they are drawn together and means for supporting the vise on 35 the bench either in operative position or in retracted position.

GEORGE W. RAYNOR.
